UNITED STATES PATENT OFFICE.

AUSTIN F. JACKSON, OF TAUNTON, MASSACHUSETTS.

DESIGN FOR A SPOON.

SPECIFICATION forming part of Design No. 21,131, dated October 27, 1891.

Application filed September 22, 1891. Serial No. 406,532. Term of patent 7 years.

To all whom it may concern:

Be it known that I, AUSTIN F. JACKSON, a citizen of the United States, residing at Taunton, in the county of Bristol and State of Massachusetts, have invented and produced a new and original Design for Handles of Spoons, Knives, Forks, &c., of which the following is a specification, reference being had to the accompanying drawing, forming part thereof.

5 The figure is an upper or face view of my design applied to a coffee-spoon.

10 The leading feature of the design is the representation of a calla-lily blossom *a*, which forms the outer end of the handle. Below the blossom there is laid upon the handle a 15 representation of the stems and leaves *b* of a

calla lily. The outer edges of the lily-blossom and also the outer edges of the leaves form the marginal edge of the spoon-handle and impart their contour to the same. 20

What I claim is—

The design for the handles of spoons, knives, forks, &c., consisting of the representation of a calla-lily blossom *a*, with leaves *b*, the outer margins of said blossom and leaves giving contour to the handle, substantially as shown and described. 25

AUSTIN F. JACKSON.
